UNITED STATES PATENT OFFICE.

STAR HENRY ROGERS, OF MACON, GEORGIA.

BOTTLE-STOPPER.

SPECIFICATION forming part of Letters Patent No. 737,025, dated August 25, 1903.

Application filed May 25, 1903. Serial No. 158,706. (No model.)

To all whom it may concern:

Be it known that I, STAR HENRY ROGERS, a citizen of the United States, residing at Ma-
5 con, in the county of Bibb and State of Geor-
gia, have invented new and useful Improve-
ments in Bottle-Stoppers, of which the follow-
ing is a specification.

This invention relates to certain new and useful improvements in bottle-stoppers; and
10 it has for its object the construction of a bot-
tles stopper and the combination therewith of
simple and inexpensive means whereby the
cork or stopper may be readily removed from
the bottle at any time without the necessity
15 of using a corkscrew or other independent
stopper-removing device and without injury
to the stopper. The attachment to the stop-
per which is designed for use in removing the
same is also adapted for use as a locking
20 means for securing the stopper in place in the
neck of the bottle when the same is designed
for shipment or storage.

To these ends and to such others as the in-
vention may pertain the same consists in the
25 novel construction of the stopper and its at-
tachments and in the peculiar combination,
arrangement, and adaptation of parts, all as
more fully hereinafter described, shown in
the accompanying drawings, and then spe-
30 cifically defined in the appended claim.

The invention is clearly illustrated in the
accompanying drawings, which, with the let-
ters of reference marked thereon, form a part
of this application, and in which drawings—

35 Figure 1 is a perspective view showing my
device in position with the stopper shown as
locked in place in the neck of the bottle. Fig.
2 is a like view of the device, the stopper-re-
moving attachment being shown in position
40 for withdrawing the stopper. Fig. 3 is a de-
tail perspective view of the stopper, parts be-
ing broken away in order to better illustrate
the construction; and Fig. 4 is a detail view
in perspective showing the several parts of
45 the stopper separated.

Reference now being had to the details of
the drawings by letter, A designates a bottle,
and B my improved form of stopper or cork,
the said stopper consisting of a body portion
50 C, which may be of cork or other substance
found adapted to the purpose. This body
portion is provided with a central opening

through which is passed a wire or shank D,
upon the lower end of which is carried and
securely attached thereto an enlarged end por-
tion E, preferably constructed of rubber, but
which may be of any other substance found
adapted to the purpose and provided in order
to produce a tight fit within the neck, thereby
preventing leaking of the bottle. The cork
or body portion of the device C is passed down-
ward on the shank D, and the upper end of
the shank is provided with a suitable flanged
head portion F, which has a bearing directly
upon the upper end of the cork. Secured to
the shank D immediately below the headed
upper end of the same are the ends of wires
G G, the body portions of said wires being
formed into loops, as shown at H H. These
loops H are bent upward and provide a means
whereby the cork may be withdrawn from the
bottle when it is desired to remove the same.
When the cork is seated, the loops are bent
down over the outer edges of the bottle-neck
and are held in position by a wire or band
75 around the neck of the bottle and extending
through the loops or other suitable means
passed about the same, which serve to hold
the stopper securely in position in the neck of
the bottle and prevent the same from being
80 accidentally displaced from any cause.

Having thus fully described my invention,
what I claim as new, and desire to secure by
Letters Patent, is—

A bottle-stopper comprising a cork which is
85 centrally apertured, a flexible end portion E
thereto, a rod D passing through said cork
and end portion, a flange at the inner end of
said rod engaging the outer convexed surface
90 of the end portion, a disk F fitted to the outer
end of the rod, a wire twisted about said rod
and formed into loops, the strands of said
wires being clamped by the disk F against
the outer end of the cork, and the loops form-
ing means for withdrawing the cork, as set
forth.

In testimony whereof I have signed my
name to this specification in the presence of
two subscribing witnesses.

STAR HENRY ROGERS.
